UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

CHANGEABLE PRINTING FORM.

Application filed March 10, 1922. Serial No. 542,532.

To all whom it may concern:

Be it known that I, HENRY C. OSBORN, a citizen of the United States, residing at Cleveland, in the county of Cuyahoga and State of Ohio, have invented a certain new and useful Improvement in Changeable Printing Forms, of which the following is a full, clear, and exact description, reference being had to the accompanying drawings.

This invention relates to a printing machine and particularly to that character of printing machine which employs a rotary printing drum, as for example, a multigraph.

The general object of the invention is to provide a printing member which is adapted for use in connection with a printing drum and which may be removably mounted on the drum.

A specific object of the invention is to provide, for use in connection with a rotary printing drum, a removable impression member having type characters thereon, the member being curved to conform to the curvature of the printing drum.

A further object of this invention is to provide a removable printing form which may be used in connection with printing drums having type holding means thereon, the removable form being provided with printing characters at an angle to the lines of type carried by the printing drum.

A more specific object of the invention is to provide a curved holding member which is adapted to be secured to a printing drum, the member having projections thereon, whereby channeled embossed strips may be secured to the drum.

An additional object of the invention is to provide a novel form of type holding member for a printing drum wherein the type channels are formed by folding and bending a sheet of metal.

Other objects of the invention will be apparent from the following description taken in connection with the accompanying drawings, wherein Fig. 1 is a perspective view of a printing strip constructed according to my invention; Fig. 2 is a perspective view of the removable holding member for the printing strip; Fig. 3 is a fragmentary plan of a rotary printing drum embodying features of my invention; Fig. 4 is a fragmentary end view of a printing drum show-

ing means for locking a removable printing character holding member in position; Fig. 5 is an end view of a portion of a rotary printing drum; Fig. 6 is a section on line 6—6 Fig. 3; Fig. 7 is a detail in elevation, showing my invention applied to a solid drum; Fig. 8 is a fragmentary section on an enlarged scale of a printing drum and associated parts constructed according to my invention.

Referring to the drawings by reference characters, I have shown at 10 a printing drum which embodies one of the features of my invention. This drum may be rotatably mounted on a suitable shaft. The periphery of the drum is shown as provided with a type bed 12 (see Fig. 8) indicated as comprising a sheet metal plate bent to form a plurality of slots defined by T heads 14 which are attached to the body portion of the bed 12 by means of the webs 15. In making the sheet metal type bed the material is bent to the proper shape and tightly compacted. Suitable impression members, such as individual type or cast slugs 16, are inserted in the slots and from these members printing is done.

It frequently happens in using machines, such as multigraphs to which my new drum is particularly adapted to be used in conjunction with the type in the rails that columns of type extending circumferentially of the drum are required. To meet such requirements, I employ the following.

A curved holder for a printing member is indicated at 20. This holder is shown as curved to fit the periphery of a drum and it may be fitted directly over the rails of a multigraph or other machine. The holding member may be secured to the drum in any desired manner. It may be provided with lugs 21 at each end each of which is adapted to be engaged by a slot in the end of resilient strap-like metal member 22, the construction at one end being illustrated in Fig. 3.

The end of the straps 22 may be folded over to engage a lever member 23 with which it may be moved to position. The straps 22 are preferably made of rather stiff metal so that the mere act of forcing the levers 23 to position behind the shoulder of the rails serves to hold the straps securely in position.

The holder previously described is indi-

cated as provided with a plurality of engaging tongues formed by upstruck projections 25. The projections are severed from the body of the holder by opposed curved slits 26. This leaves the body of the projection connected with the body of the holder by narrow neck portions 28.

The projections just described are adapted to serve as securing means for a curved printing member which constitutes one of the features of my invention. This curved printing member which is shown for example, in Fig. 1, comprises a strip 30 of metal or other material having printing characters 31 embossed in its upper surface while the sides of the member are indicated as turned down and inwardly, as at 33, to provide engaging flanges. These flanges may be notched, as at 34, to allow ease in manufacture and to allow the strip 30 to be curved as desired. A suitable stop lug 36 on the end of the printing strip 30 may serve to accurately position the strip in use.

25 The embossed strips 25 may comprise single lines of type, or two or more lines may be arranged on one bed. In the latter case the impression member would extend over two or more rows of holding members 30 23.

The inwardly projecting flanges 33 on the strip are adapted to extend beneath the projections 25 on the holding member and thus securely hold printing members in place. 35 The printing strip is secured to the holding member by a sliding movement, since the material is too rigid to permit the strip being otherwise placed in position.

I preferably make the type 16 carried by 40 the rails of the drum of such height that they will be on a level with the printing characters 31 on the printing strips 30 when the latter are in place on the holder 20, thus enabling a uniform impression to be secured.

50 In Fig. 4 it will be noted that the type rails 14 are indicated as solid members and are not made of sheet metal. Such solid metal rails are well known in the art and form no part of my present invention, although I wish it to be understood that the holding member and the embossed printing strip are adapted for use on either the sheet metal or the solid metal rails.

55 In some instances, it is desirable to mount the holding member 20 directly upon a printing drum instead of placing it over type rails. Such a construction is shown in Fig. 7 wherein a portion of a drum is indicated at 50, a holding member 20' being seated thereon while a printing strip 30' having characters 31' thereon is indicated as secured to the holding member. In this modification, the holding member may be

secured to the drum by the fastening device 65 similar to that shown in Fig. 3 and comprising as shown in Fig. 7 a stud 21' on the holding member 20', a short strap 22' and a lever member 23' which engages a notch 51 in the drum 50.

70 My invention is particularly adapted for use when a quick change in the printing characters carried on the drum is required, since when using my device the type need not be removed singly but an entire linear group of lines may be removed and another quickly substituted.

75 Having thus described my invention, I claim:

1. The combination of a rotary drum, a 80 type holding member secured to the drum and having a plurality of separated projections thereon extending above the surface of the member and arranged in a circumferential row, and an embossed print-strip 85 extending circumferentially and overlying said projections and having flanged edges engaging the projections.

2. In a printing machine, a rotary printing drum having type rails, type in the 90 rails and a second member extending circumferentially of the drum and having type thereon disposed at the same height as said first mentioned type.

3. The combination with a printing drum 95 of a plate secured on the periphery of the drum, holding means carried by the plate and extending circumferentially and having overhanging lateral edges, and an embossed printing strip extending circumferentially 100 and mounted directly over said holding means and having inwardly flanged edges extending beneath the laterally overhanging portions of the holding means.

4. A rotary printing drum having type 105 holding rails thereon, and an additional printing character holding member secured over the rails, said member having circumferentially extending means thereon for engaging a printing member.

5. A character printing strip comprising 110 a body portion having characters thereon, and a pair of side flanges, said flanges being notched.

6. An embossed sheet metal character 115 printing strip comprising a top portion and a pair of side flanges, the continuity of said side flanges being interrupted, whereby the strip may be made to conform to the curvature of a printing drum.

120 7. A printing frame comprising a holder adapted to be secured to a printing machine, and an impression member secured to the holder, said impression member comprising a flanged metal strip having embossed printing characters thereon, the flanges of said strip being notched.

125 8. In combination with a printing ma-

chine, a printing member, said member comprising a flanged metallic strip having embossed characters on one face thereof, and having notches in the sides thereof, and 5 means to secure the member to the machine.

9. In a printing machine, the combination of a rotary printing drum having T rails thereon adapted to receive type, a printing character holding plate secured to said 10 drum over some of said rails, said plate having means projecting above its surface and extending circumferentially of the drum for securing printing characters thereto.

15 10. In combination with a printing drum having T rails thereon, a printing member mounted on said T rails, resilient clips to hold said plate in position, surface projections carried by said plate, and a character printing slip secured to the plate by 20 said projections.

11. In combination, in a printing machine, a rotary drum, a type holding member secured to the drum and having projections extending above the surface thereof, said projections being arranged in a 25 straight line, and a printing member arranged to fit upon the projections and having portions which extend beneath the projections. 30

12. In a printing machine, a rotary drum, means on the drum for securing type thereto, said means comprising a strip of material bent to provide a curved portion to 35 rest on the drum, and a plurality of spaced upwardly extending portions, said upwardly extending portions being flattened to provide T-shaped rails.

13. A printing strip comprising a top 40 portion adapted to be bent to conform to the curvature of a printing cylinder, printing characters on said top portion, side flanges on each side of said top portion, said flanges being interrupted, whereby the 45 top may be bent, said flange being bent toward each other to afford holding portions,

whereby the printing strip may be held in position.

14. In combination, a printing member having a bed thereon, a line of impression members extending longitudinally of said bed, a holding member secured transversely of said bed, said holding member having means thereon for engaging an impression member, a second impression member engaged by said means, said last mentioned impression member extending transversely of said first mentioned impression member. 55

15. The combination of a printing machine and an impression member, means to 60 lock said impression member to said machine, said means comprising a strip of material having means at one end for engaging the impression member and having a locking portion for engaging the print- 65 ing machine.

16. As a means for securing an impression member to a printing machine, a strip of material having an operating member at one end and having a transverse fork at 70 the other end for engaging an impression member.

17. In a printing machine, the combination of a rotary printing drum having T rails thereon adapted to receive type, 75 grooved type mounted on said rails, said rails extending in a direction parallel to the axis of the printing drum, a sheet metal plate overlying some of said rails beyond the type and having projections arranged circumfer- 80 entially a printing member having impression characters thereon secured to said projections said characters extending in a direction circumferentially of the drum, the height of the grooved type in the rails and 85 the impression characters on the circumferential printing member being the same whereby a clear impression may be had.

In testimony whereof, I hereunto affix my signature.

HENRY C. OSBORN.
